UNITED STATES PATENT OFFICE

FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE

COOLING DEVICE

Application filed December 17, 1926. Serial No. 155,433.

This invention relates to cooling systems in general and more particularly to a unit of such a system adapted to be cut out while the system remains active.

5 In cooling systems, it is often desirable to cut out either partly or altogether a unit thereof without danger of freezing as for instance, the unit for cooling the drinking water, the latter usually not being used at night.

10 In soda fountains particularly, one of the greatest troubles is the danger of freezing the water when the demand is slight and the necessity at the same time for being able to take care of a sudden increase in demand.

15 It is accordingly an object of this invention to provide an efficient cooling unit which may be cut out either partly or altogether to prevent over cooling or freezing of a part of the system not in use without interfering with 20 the rest of the system.

It is also an object of this invention to provide such a unit which can take care of a sudden fluctuation in demand without danger of freezing when the demand is slight and at 25 the same time having sufficient capacity to take care of peak loads.

Other and further objects of this invention will be apparent from an examination of the specification and claims in connection with 30 the accompanying drawings wherein,

Fig. 1 represents a fragmentary longitudinal sectional view of a portion of a cooling system showing a unit thereof.

Fig. 2 is a fragmentary plan view of the 35 same with parts removed.

Referring to the drawings, numeral 3 represents a cooling water compartment containing water which may be the drinking water itself or merely the medium by which the 40 drinking water is cooled, the latter in such a case might be circulated through coils immersed in the water in the said compartment.

Submerged beneath the water within the compartment 3 is a horizontal double wall cylinder 4 including an outer cylinder 5 and an inner cylinder 6, the two cylinders 5 and 6 forming a thin refrigerant chamber 7 adapted to receive a refrigerant in the form of a gas and serves as a heat transfer unit. The 50 chamber 7 is very thin and has a maximum of

conducting area in proportion to its volume so that it may cool the water in the compartment 3 very rapidly when the refrigerant is circulating therethrough. The ends of the chamber 7 are sealed as by welding the respective corresponding ends of the cylinders 5 and 6 together. The cylinder 4 surrounds a section 8 of a refrigerant line leading from the low pressure side of a mechanical refrigerating apparatus. The section 8 is provided with detachable couplings 9 and 10 for removably connecting it in the refrigerant line 11 in the low pressure side, terminals 12 and 13 of which project into the compartment 3 from opposite walls respectively thereof.

The refrigerant normally circulates in the form of an expanded and therefore cold gas through the line in the direction from the terminal 12 to the terminal 13. A valve casing 14 is interposed in the section 8 between the coupling 9 and the middle of said section. A T-connection 15 is likewise interposed in the section 8 between the middle thereof and the coupling 10. This connection is connected by pipe 16 to an upper portion of the chamber 7, while the lower end 17 of the valve casing 14 is connected to the bottom of said chamber. A valve stem 18 in the housing 14 carries a valve disk 19 at its lower end and is adapted to be screwed up or down by a handle 21 to vary the admission of the refrigerant from the line 11 to the chamber 7, a passage 22 in the housing 14 establishing communication between said line and valve. The stem 18 is provided with vertically spaced threaded portions 23 on either side of a diametrically reduced portion 24. When the disk 19 is seated, the refrigerant will flow directly through the casing but as the disk is moved away from its seat, the portion 23 correspondingly shuts off direct flow through the casing and permits inward flow of refrigerant into the chamber 7 with consequent cooling effect.

When the valve 19 is closed, the refrigerant passes practically unrestrictedly around the portion 24 through the section 8 without circulating through the chamber 7.

The cylinder 4 is provided with a recess 25 extending from its right hand edge to facilitate assembly and dispose the valve handle 100

in accessible position. The cylinder 4 is preferably packed with a suitable heat insulating substance 26 to minimize the effect of the refrigerant in the section 8. Portions 27 and 28 of the substance 26 extend from opposite sides respectively of the cylinder 4 and are moulded around the corresponding parts of the line 11 which are outside of said cylinder and within the compartment 3 so that when the valve 19 is closed, the refrigerant flowing in the said line will have no effect upon the water in the said compartment.

It will be apparent that when it is not desired to utilize the chamber 7 to cool the water in the compartment 3, the portion of the pipe 8 which extends between the housing 14 and the T connection 15 may be used as a by-pass to shunt all of the refrigerant instead of permitting any of it to circulate past the valve 19 into said chamber and out through the pipe 16.

It will be obvious that a suitable expansion valve might be used in place of the valve 14 and the chamber 7 utilized as an expansion chamber.

I am aware that many changes may be made without departing from the principles of this invention and I therefore do not wish to be limited to the details shown or described.

I claim:

1. A refrigerating unit adapted to be inserted in a refrigerant line, comprising a cooling receptacle adapted to receive the refrigerant and be operatively associated with a compartment for cooling the same, means for circulating the refrigerant through said receptacle and means in the compartment and insulated from the same for by-passing said refrigerant past said receptacle.

2. A refrigerating unit adapted to be inserted in a refrigerant line, comprising a double walled cylinder, the two walls thereof forming a chamber therebetween adapted to receive the refrigerant, means for circulating a refrigerant through said chamber, means extending longitudinally through said cylinder for by-passing said refrigerant past said chamber, and means for insulating said by-passing means from said receptacle.

3. The combination with a line containing a refrigerant, of a double walled cylinder surrounding said line, the two walls of said cylinder forming a chamber therebetween, and means for adjustably admitting refrigerant from said line to said chamber and permitting the flow of some of the refrigerant past said chamber even when admitting some of said refrigerant to the chamber.

4. The combination with a compartment adapted to contain a liquid to be cooled, of a receptacle in said compartment adapted to be immersed in said liquid, said receptacle being in the form of a double walled cylinder, the

two walls of said cylinder forming a chamber therebetween, means for circulating a refrigerant through said chamber, and means in the compartment and insulated from said fluid for by-passing said refrigerant past said chamber.

5. The combination with a compartment adapted to contain a liquid to be cooled, of a refrigerant line extending through said liquid, a double wall cylinder within the compartment and surrounding said line, the two walls of said cylinder forming a chamber therebetween, means for circulating refrigerant from said line through said chamber, means for by-passing said refrigerant past said chamber and means for insulating said last means from said liquid.

6. A liquid cooling device comprising, a hollow cylindrical heat transfer unit adapted to be submerged in the liquid to be cooled, a pipe extending longitudinally through said unit, and adapted to be interposed in a refrigerating line, and means whereby any desired portion of the refrigerant flowing through said line may be directed into said unit to cool the same.

7. A liquid cooling device comprising a hollow cylindrical heat transfer unit adapted to be submerged in the liquid to be cooled, a pipe extending longitudinally through said unit and adapted to be interposed in a refrigerating line, and a valve in said line for controlling the flow of refrigerant, the body of said valve being substantially within said unit and the handle projecting outside.

In witness of the foregoing I affix my signature.

FRENCH E. DENNISON.
